UNITED STATES PATENT OFFICE.

HAROLD A. GREENWALD, OF DETROIT, MICHIGAN, ASSIGNOR TO THOMAS C. WHITEHEAD, OF DETROIT, MICHIGAN.

COMPRESSOR.

Application filed June 13, 1927. Serial No. 198,572.

The invention relates generally to compressors for refrigerating apparatus and finds particular utility in a means for preventing dilution of oil in the crank case.

In the operation of compressors a serious disadvantage has been commonly experienced by the leakage of gas past the piston into the crank case, thus building up pressure in the latter and diluting the oil contained therein and proving detrimental to the working parts of the apparatus. This objectionable feature is more than compensated for in the present invention by the novel construction of the compressor in which means is provided for permitting escape of the gas leaking past the piston prior to its entrance in the crank case.

The invention has also among its objects to simplify, render more efficient and improve generally devices of this character and these as well as other objects, advantages and novel details of construction will be made more apparent as this description proceeds, especially when considered in connection with the accompanying drawings wherein,

Figure 1 is a sectional elevation of a compressor embodying my invention, and

Figure 2 is a sectional view taken on line 2—2 of Figure 1.

Referring now to the drawings in which like reference numerals designate corresponding parts, the reference character 10 designates a compressor having a crank case 11 containing a supply of lubricant, and 12 a crank shaft journalled in suitable bearings 13. Formed, preferably although not necessarily, integral with the casing 10 is a cylinder 14 within which a piston 15 is reciprocably mounted. The piston is connected by means of a wrist pin 15' and a connecting rod 16 to the crank shaft 12. The cylinder 14 is provided with a port 18 which communicates with a suitable conduit (not shown) by means of which the refrigerant or the gas compressed in the chamber is conducted away. In the present instance the port 18 is connected to a condenser.

As shown the cylinder 14 has a chamber 21 formed at one side thereof and provided with an intake opening 22, which communicates with the expansion coils when the invention is used as a part of a refrigerating apparatus.

Communication between the chamber 21 and the cylinder 14 is established by means of a restricted passage 23 in the cylinder wall 14 near the top of chamber 21 and spaced somewhat above the aperture 22. Consequently on the downward or suction stroke of the piston 15, the refrigerant or other gas will be drawn from chamber 21 through opening 23 into the cylinder 14 and upon a compression stroke will be compressed therein and forced out through the port 18. Obviously upon the downward or suction stroke of the piston 15, a lower pressure is created in the cylinder 14 causing a corresponding lower pressure to obtain in chamber 21 thus drawing the refrigerant in through the opening 22.

In practice, a certain percentage of gas contained in the cylinder 14 leaks past the piston and into the crank case diluting the oil contained therein, proving detrimental to the working parts of the apparatus as, for example, the seal.

In the present invention this objectionable feature is eliminated by the novel construction of the piston and wrist pin. As shown, the wrist pin 15' is of hollow construction open at both ends, and the piston 15 is formed with aligned circumferential grooves 24 and 25 communicating with the wrist pin. Thus any gas that leaks past the usual piston ring will be collected by the grooves 24 and 25 and will flow into the wrist pin, due to the fact that the depth of the grooves is substantially greater than the distance between the cylinder wall and piston. In practice, the wrist pin serves as a surge chamber or reservoir for the gas which, upon entering the wrist pin, builds up a relatively high pressure therein until the piston is in substantially its uppermost position, whereupon the gas will be discharged through the opening 23 and into the arresting chamber 21.

From the foregoing, it will be readily apparent that the gas leaking past the piston is arrested prior to its entrance into the crank case and conveyed back to the chamber 21, whereupon the gas is permitted to join the refrigerant in circulation.

While it is believed that from the foregoing description, the nature and advantage of my invention will be readily apparent, I desire to have it understood, that I do not limit myself to the specific construction shown and

described and that such changes may be resorted to when desired as fall within the scope of the claims.

What I claim as my invention is:

- 5 1. A compressor assembly including a cylinder, a piston reciprocable in said cylinder having a passage for receiving the gas leaking past the piston, and a wrist pin having a recess therein communicating with the passage.
- 10 2. A compressor assembly including a cylinder, a piston reciprocable in said cylinder formed with a circumferentially extending groove for receiving the gas leaking past the piston, and a hollow wrist pin communicating with the groove.
- 15 3. A compressor assembly including a cylinder, an arresting chamber adjacent thereto and having a passage communicating therewith, a piston reciprocable in said cylinder having a circumferentially extending groove for receiving the gas leaking past said piston, and means associated with said piston for conducting the escaped gas through said
- 20 25 passage into the arresting chamber.

4. A compressor assembly including a cylinder, an arresting chamber adjacent thereto and communicating therewith, a piston reciprocable in said cylinder having a circumferentially extending groove for receiving the gas leaking past said piston, and a hollow wrist pin communicating with said groove for collecting the escaped gas and discharging the same into said arresting chamber.

5. A compressor assembly including a cylinder, a piston reciprocable in said cylinder having a circumferentially extending groove for receiving the gas leaking past said piston, a hollow wrist pin communicating with said groove for collecting the escaped gas, and an arresting chamber adjacent to said cylinder having a passage communicating therewith operable to conduct gas from said chamber into said cylinder in one position of the piston and to permit a discharge of the escaped gas entrapped in the wrist pin into the arresting chamber in another position of the piston.

In testimony whereof I affix my signature.
HAROLD A. GREENWALD.
